E. FLETCHER AND R. L. WICKES.

PHONOGRAPH.

APPLICATION FILED MAY 29, 1918.

1,322,890.

Patented Nov. 25, 1919.

UNITED STATES PATENT OFFICE.

ELMER FLETCHER AND ROSCOE L. WICKES, OF CHICAGO, ILLINOIS, ASSIGNEES TO
FLETCHER-WICKES CO., OF CHICAGO, ILLINOIS, A CORPORATION OF ILLINOIS.

PHONOGRAPH.

1,322,890.

Specification of Letters Patent. Patented Nov. 25, 1919.

Application filed May 28, 1918. Serial No. 237,190.

To all whom it may concern:

Be it known that we, ELMER FLETCHER and Roscoe L. WICKES, both citizens of the United States, and residents of Chicago, in the county of Cook and State of Illinois, have invented certain new and useful Improvements in Phonographs, of which the following is a full, clear, and exact description.

10 The invention relates to phonographs.

One object of the invention is to provide an improved tone arm having walls, whereby the vibration resultant from sound passing therethrough, is materially reduced, it having been found in practice that the tone is clearer when the tone-arm is constructed to measurably reduce the vibration in the walls thereof.

In practice, it has been found that the best results are obtained by having the needle exert a certain pressure upon the record and that records of different manufacture or made by different processes require different pressures for the attainment of the best results. To meet this condition, it has heretofore been proposed to apply a spring with a regulable tension, but this has been found unsatisfactory, because of the impossibility of ascertaining the degree of pressure resulting from a variation in the adjustment of the spring. Another object of the present invention is to provide improved means by which the pressure of the needle on the record may be reliably and definitely varied so that a certain pressure may be used for records of one make and another pressure for other makes. This object is attained by providing a weight-ring which is capable of adjustment to vary the pressure of the needle on the record.

Another object of the invention is to provide an improved rotatable connection between the tone arm and the sound box, whereby the needle is caused to assume the same angle relatively to the record, either when the sound box is in position for the transverse vibration of the needle or when the sound box is positioned for vertical vibration of the needle.

50 The invention consists in the several novel features hereinafter set forth and more particularly defined by claims at the conclusion hereof.

In the drawings: Figure 1 is a side elevation of an instrument embodying the

invention. Fig. 2 is a plan. Fig. 3 is a section. Fig. 4 is a detail section of the adjustable weight-ring. Fig. 5 is a section taken on line 5—5 of Fig. 3. Fig. 6 is a section taken on line 6—6 of Fig. 1. Fig. 7 is a detail section of the connection between the tone-arm and the sound box.

A supporting board 8, which may be of any suitable construction, carries a suitable bearing ring in which the tone-arm is mounted for limited universal movement, so that it may be moved vertically and laterally. The bearing ring consists of an annular top member 9 having a flange lapsing and seated on the board 8 and an annular lower member 10 secured to the member 9 by screws 11. An annular groove 12 is formed in the bearing-ring and contains a ring 13 and three anti-friction balls 14 are interposed in spaced runways between the bearing-ring and the collar 12, so that the tone-arm may be easily rotated.

The tone-arm comprises a member 19 and an elbow-shaped outlet member 15 which has a spherical portion 16 fitting in the collar 12 and pivotally connected thereto by two alined pins 17, which are fixed in the collar 12. A pin 17' is disposed diametrically opposite to the horizontal member 19 of the tone-arm, and the other two fulcrum pins 17, which extend into pivot-holes in member 15, are disposed inwardly of the center of the longitudinal axis of outlet member 15, so that the fulcrum, about which the arm swings vertically, is disposed inwardly of the center of the outlet member. If desired, the outer portion 15' of member 15 is weighted or thickened to aid in distributing the weight at both sides of the tone-arm fulcrum. Pin 17' extends into a vertical slot 15' in member 15 and serves as a stop to limit the vertical swinging of the entire tone-arm. The entire collar 12 is rotatable horizontally with the tone-arm, and the arm may be shifted vertically about its fulcrum (pins 17), relatively to the collar 12. This construction exemplifies one in which the fulcrum, about which the tone arm may be swung vertically, is disposed inwardly of the center of the outlet member, so that the weight of a considerable portion of the outlet member will be disposed on the outside of the fulcrum so as to assist in counterbalancing the weight of the sound box and horizontal member of the tone arm.

A ring 23 is rotatably held around the lower portion of the outlet member 15 of the tone-arm, a shoulder 24 being formed on said member to rotatably support this ring. This ring comprises a solid portion 25 and a hollow portion 26. A pin 27 on the member 15 serves as a stop for limiting the rotation of the ring, so that the solid or weighted portion may be adjusted into position under the tone arm or to a diametrically opposite position. The purpose of this construction of ring is to provide an adjustable counterweight whereby the proportion of weight on the opposite sides of the supporting axis of the tone arm may be varied to correspondingly vary the pressure of the needle on the record. A slot 28 is formed in the ring 23 so that it can be placed in position on and removed from the tone arm.

In practice, shift of the ring from the position shown in Fig. 4, to a diametrically opposite position, is usually sufficient to adapt the structure for different types of machines.

The horizontal member 19 is removably secured to the outlet or elbow member 15 by an interlocking or bayonet catch 20, which may be of usual construction, so that the tone arm may be removed and replaced, and if desired, one of different length may be substituted. In cross-section, the members 19 and 15 of the tone-arm are approximately polygonal and, the surrounding walls are thicker at the ridges, as shown at 21, than at the intermediate portions 22, so that, in effect, the surrounding wall is made up of longitudinal portions varying in thickness and this, in practice, has been found to materially reduce vibration in the walls, by reason of the greater relative rigidity of the thicker portions. This construction exemplifies one in which the vibration of the walls of the tone arm is reduced by forming the walls with longitudinally reinforced or thickened portions.

In practice, it is customary to provide a pivotal connection between the tone arm and the sound box, whereby the latter may be shifted from a vertical position with the needle vibrating transversely to an inclined position with the needle positioned to vibrate vertically, to adapt the machine for playing different records. It is desirable to maintain the same angle, approximately 35°, between the needle and the record during either position of the sound box. A tubular connecting member 28' has a hollow stem 29 which is rotatably held in the outer end

of the member 19. This stem is removably connected to said member by a pin 30 and an angular slot formed to limit the movement of the member 28' to correctly position the sound box 31 in either of its positions. The tubular connecting member 28', when the box is in position shown in full lines in Figs. 1 and 2, extends, as at 36, downwardly and laterally to one side of the tone-arm, and is then reversely curved, as at 37, to open laterally into the outlet 32 in one side of the sound box disposed at the other side of the arm, the bend 36 being, as at 40, indirect or curved below a direct line from the end of member 19 to the axis of the sound box outlet, as shown in the drawings. The needle 33 and its support may be of any suitable construction, as well understood in the art. This peculiar form of bend in the connecting member between the tone-arm and the sound box avoids sharp turns in the sound passage and causes the sound box, when swung from one side of the center of the tone-arm to the same distance at the other side of the center, (see dotted lines) to be located in such a position that the angle of the needle, relatively to the record, will be substantially the same and correct in either of its positions.

The invention is not to be understood as restricted to the details set forth, since these may be modified within the scope of the appended claims, without departing from the spirit and scope of the invention.

Having thus described the invention, what we claim as new and desire to secure by Letters Patent, is:

1. In a phonograph, the combination of a support, a tone arm, a pivotal connection between the support and the tone arm, and a weight mounted to rotate around the tone-arm to vary the pressure of the needle on the record.

2. In a phonograph, the combination of a support, a tone arm, a pivotal connection between the support and the tone arm, and a weight-ring mounted on the tone arm and rotatable around it to vary the pressure of the needle on the record.

3. In a phonograph, the combination of a tone arm, a support, and a pivotal connection between the tone arm and the support, the walls of the tone arm having longitudinal portions of different thickness to reduce the vibration thereof.

ELMER FLETCHER.
ROSCOE L. WICKES.
